UNITED STATES PATENT OFFICE.

EDWARD H. WHITNEY, OF CAMBRIDGE, ASSIGNOR TO THE DOVER STAMPING COMPANY, OF BOSTON, MASSACHUSETTS.

DUST-PAN.

SPECIFICATION forming part of Letters Patent No. 554,848, dated February 18, 1896.

Application filed March 22, 1895. Serial No. 542,755. (No model.)

To all whom it may concern:

Be it known that I, EDWARD H. WHITNEY, a citizen of the United States, residing at Cambridge, in the county of Middlesex and State 5 of Massachusetts, have invented a new and useful Improvement in Dust-Pans, of which the following is a full, clear, and exact description, reference being had to the accompanying drawings, forming a part of this specification in explaining its nature.

The invention relates to the handle of the dust-pan and the preparation or shaping of the body of the pan to receive it, the whole being designed to provide a stiff and strong 15 construction and organization.

Referring to the drawings, Figure 1 is a view in perspective of the dust-pan inverted. Fig. 2 is a view in elevation looking from the front of the pan. Fig. 3 is a view in section 20 of a portion of the body of the pan and of the handle. Fig. 4 is a section upon the dotted line of Fig. 1. Fig. 5 is a perspective of the handle detached.

The handle A is made from a flat piece of 25 sheet metal, which is given a suitable outline by dies and is thus provided with three arms a a' a² and with a tongue a³ and a hole a⁴, and the blank thus obtained is shaped to the form represented in the figures—namely, its 30 edges a⁵ a⁶ are brought together, the tongue a³ passed through the hole a⁴ and bent backward, as represented in Fig. 4, thus securely tying the two edges together—and the arms a a' a² are bent to the shape represented in 35 the figures, and so that the arms a a' are adapted to be fastened to the back of the part B of the body and the arm a² to extend over the top of the back and upon the front side thereof, (see Fig. 3,) where it is riveted to 40 the back. The handle thus formed is hollow and tapering inward from its outer end, and it is cut away between the arms a a', so that no portion of the handle shall extend below the bottom of the body. The arms are separated 45 from each other by appropriate recesses, and the arms a a' diverge from each other and have flat sections at their ends which bear against the back of the pan, while the arm a² passes over the top and extends down 50 its front.

The attaching-rivets which I prefer to use

in securing the arms to the back of the body are shown in the figures. This provides a very simple and strong way of attaching or securing the handle to the pan, and by cutting away the section of the handle between the arms a a' provision is obtained for the ready heading of the rivet used in attaching the arm a² to the back, as it permits one part of the heading-tool to be inserted between the 60 arms a a'.

To enable thin metal to be used for the body, as well as to properly reinforce the back to receive the handle, I have formed in the back b, by stamping, the ribs b', which 65 extend from the stiffening-flange b² to and into the bottom of the pan; and I also further stiffen it by the reinforcing-rib b³, which not only serves to strengthen the structure, but is also made sufficiently deep to provide 70 a foot or rest b⁴ integral with the rest of the body and upon which it rests when on the floor and which acts to maintain it in a level position when so placed.

The handle being hollow and tapering affords means by which it may be attached to 75 a longer or wooden handle, if desired, the supplemental handle, of course, entering the cavity of the hollow handle.

While I prefer that the edges of the handle 80 be united by one or more tying-tongues of the character specified, as this structure provides a very desirable one in that it is strong and prevents the parts from separating either way, yet the union of the edges may be made 85 by overlapping or in any other of the common ways used by tinsmiths or metal workers.

Having thus fully described my invention, I claim and desire to secure by Letters Patent 90 of the United States—

As an improved article of manufacture, a dust-pan having in its back the two corrugations or ribs b' separated from each other and extending from the upper stiffening edge or flange b² into the bottom section of the pan, 95 the stiffening-foot b³ formed by a deep corrugation in the bottom and back of the dust-pan, the ribs or corrugations b' and the corrugations b³ being so located at the back as to provide an unobstructed plane or level surface 100 for the attachment of the handle, and the handle A having the arm a² which extends

2
over the stiffening-flange on the inner side of the back and is riveted by a rivet passing through it and the back and the arms a , a' , which diverge from each other and the handle 5 and are riveted to the back closely to the ribs or corrugations b' by rivets extending through outwardly-turned sections of the arms outside the line of the handle and whereby the said

arms and the ribs b' , the arm a^2 and the foot b^3 co-operate to strengthen the back and provide stiffness between the body and the handle of the pan, substantially as described.

EDWARD H. WHITNEY.

In presence of—

AGNES M. ESTES,
GEO. L. HACKNEY.
